UNITED STATES PATENT OFFICE.

ANDRÉ M. MERTZANOFF, OF NEW YORK, N. Y., ASSIGNOR TO AMERICAN RADIATOR COMPANY, OF CHICAGO, ILLINOIS, A CORPORATION OF NEW JERSEY.

BOILER JACKET.

Application filed August 11, 1921. Serial No. 491,454.

My invention relates to improvements in coverings or jackets for boilers and other structures, and the same has for its object more particularly to provide a simple, convenient and efficient jacket or covering which may be readily attached to or removed from a boiler.

Further, said invention has for its object to provide a jacket or covering composed of a plurality of parts so secured together that the same may be easily fitted upon and secured to a boiler.

Further, said invention has for its object to provide a covering or jacket for boilers which consists of a plurality of similar parts secured together at their adjacent edges by a member which will allow of a limited movement of said parts with respect to each other.

Further, said invention has for its object to provide a covering or jacket of the character specified which may be provided on its inner sides with suitable insulating material.

Further, said invention has for its object to provide a covering or jacket of the character specified having means provided thereon adjacent to its free ends whereby the same may be readily secured to cooperating means provided upon the boiler.

Further, said invention has for its object to provide a covering or jacket which will completely cover the portion of the boiler intermediate its front and back sections, and form a top and side walls wholly concealing the intermediate sections of the boiler.

Further objects will in part be obvious, and in part be hereinafter pointed out.

To the attainment of the aforesaid objects and ends my invention consists in the novel details of construction, and in the combination, connection and arrangement of parts hereinafter more fully described and then pointed out in the claims.

In the accompanying drawings forming part of this specification wherein like numerals of reference indicate like parts—

Figure 1 is a front view, partly broken away, showing a boiler provided with one form of jacket constructed according to, and embodying my said invention;

Fig. 2 is a top view of the same partly broken away;

Fig. 3 is a side elevation partly broken away;

Fig. 4 is an enlarged detail transverse section showing the manner of connecting the jacket sections together;

Fig. 5 is an enlarged detail side view showing a portion of the side wall of the jacket with the spring attaching means thereon, and

Fig. 6 is a detail transverse sectional view showing a slightly modified form of jacket for use in connection with boilers of more than ordinary width.

In said drawings 10 designates a boiler which is herein shown as of the sectional type comprising a front section 11, a back section 12, and a series of intermediate sections 13. The front section 11 is provided with the usual flue openings, fuel opening, slicing opening and ash pit opening which are respectively provided with the usual doors 14, 15, 16 and 17.

The front section 11 and the back section 12 of the boiler are of greater outline than the intermediate sections 13 so as to provide a space at the top and the sides of the boiler between the outer surface of the intermediate sections 13 and the outline of the front and back sections of the boiler when the several parts thereof are duly assembled. The front and back sections are provided upon their inwardly facing or opposing surfaces, with shoulders 11^a, 12^a which are arranged adjacent to the top and vertical edges of said sections and serve partly to retain a jacket hereinafter described.

The intermediate sections 13 are provided at their lower ends, at each side, with rounded projections 18 in which are disposed nipples which serve to connect said sections, and directly above said projections 18 the several intermediate sections 13 are provided with recessed portions 19 to accommodate the longitudinal tie-rods or bolts 20. One end of each tie-rod 20 is provided with a nut 21 whereby the several sections 11, 12 and 13 of the boiler may be drawn together and secured in their assembled position.

22 denotes a jacket which is preferably made of sheet metal and composed of two similarly-shaped portions or sections 22^a, 22^b. Each section or portion 22^a, 22^b comprises a laterally-extending portion 23 and a vertical portion depending therefrom.

The adjacent inner edges of the laterally-extending portions 23 are turned inwardly to form longitudinal flanges 24 which are engaged by the longitudinal flanges 25 of a

key or securing member 26. The flanges on the portion 23 which engage with the flanges on the connecting members 26 are so constructed that they will allow of slight movement between the portions so that the member 26 will act as a hinge connection. The lower edge of each vertical portion 22^a, 22^b, of the jacket is provided with an inwardly turned flange 27 which engages with the projections 18 of the intermediate boiler sections.

On the inner side of each section 22^a, 22^b, adjacent to its lower or free end, is provided a plurality of spring clips 28, each comprising a back 29^a, and a pair of outwardly extending curved members or fingers 30^a arranged in spaced relation to each other which are adapted to engage with the tie-rods 20 whereby to secure the jacket 22 duly in place upon the boiler.

The inner sides of the vertical portions or side members 22^a, 22^b, and the inner sides of the laterally projecting portions 23 of the jacket are provided with an insulating lining composed of sheets or layers 29 of asbestos, felt or other suitable heat-lagging material. The said insulating layers are of such thickness that they will substantially or nearly fill the space between the outer surfaces of the intermediate boiler sections 18 and inner surfaces of the top and side walls of the jacket 22.

At Fig. 6 is shown the upper portion of a modified form of jacket 30 comprising the angular side members 31, and an intermediate section 32 which may be made in several widths in order to adapt the jacket to boilers of different widths. The edges of the laterally-extending portions 33 of the side members 31 are provided with inwardly turned edges 34, and the corresponding edges of the intermediate section 32 are provided with similarly inturned edges 35. The inner edges of the laterally-projecting portions 34, and the adjacent edges of the intermediate section 32 are secured together by keys or securing members 36 each of which has its opposite longitudinal edges turned inwardly so as to permit of a sliding engagement thereof with the flanges 34 and 35 of the side members 31 and the intermediate section 32 of the jacket.

In operation the boiler is first assembled in the usual manner, and thereupon the adjacent flanged edges of the jacket portions 23 are secured together by means of the key 26 which is slid into engagement with the inturned flanges 24 on said laterally-extending portions 23. Thereupon the jacket is adjusted in position over the boiler intermediate the front and back sections thereof and caused to engage with the shoulders 11^a, 12^a of said front and back sections. The lower or free ends of the side walls are capable of being spread slightly outward

without liability of injuring the jacket by reason of the hinged connection provided by the key or securing member 26. As soon as the jacket has been fully adjusted between the front section 11 and back section 12 of the boiler the spring-attaching members 28, on the inner sides thereof adjacent to its lower or free edges will be in position opposite the longitudinal tie-rods 20, and thereupon it merely becomes necessary to press the lower or free ends of the vertical portions of the jacket inwardly to cause the attaching members 28 to snap into engagement with the tie-rods 20 and thereby secure the jacket in position upon the boiler.

In order to remove the jacket, when it becomes necessary to dismount the boiler or to obtain access thereto for any other purpose, it merely becomes necessary to grasp the lower or free edges of the vertical portion of the jacket and draw the same outwardly so that the spring-attaching members 28 may be released of their engagement with tie-rods 20 wherein the entire jacket may again be removed from the boiler.

Having thus described my invention what I claim and desire to secure by Letters Patent is:—

1. The combination with a boiler formed of a series of sections, of a jacket comprising a horizontal member and vertical side members extending therefrom, attaching means on said jacket members, and means for securing the boiler sections together adapted to cooperate with the attaching means on said jacket whereby to secure said jacket in position upon said boiler, substantially as specified.

2. The combination with a boiler formed of front, back and intermediate sections and means for securing the boiler sections together, of a jacket comprising a U-shaped member embracing the portion of the said boiler intermediate its front and back sections, and its free edges detachably engaging the means for securing said boiler sections together, substantially as specified.

3. The combination with a boiler formed of a series of sections and having its front and back sections of greater outline than its intermediate sections, means for securing said boiler sections together, a jacket disposed upon said boiler intermediate its front and back sections and in spaced relation to said intermediate sections, and means on said jacket adapted to engage with said means for securing said boiler sections together whereby to secure said jacket in position upon the boiler, substantially as specified.

4. The combination with a boiler formed of a series of sections and having its front and back sections of greater outline than said intermediate sections, said intermediate sections being provided on their sides with recesses, connecting rods located in said re-

cesses serving to secure said front, intermediate and back sections together, a jacket embracing the part of the boiler intermediate its front and back sections, and resilient members on the sides of said jacket adapted to engage said connecting rods whereby to hold said jacket in position upon the boiler, substantially as specified.

5. The combination with a boiler formed of a series of sections and having its front and back sections of greater outline than said intermediate sections; said intermediate sections being provided at their sides with recesses, connecting rods located in said recesses, serving to secure said front and back sections together, a jacket embracing the part of the boiler intermediate said front and back sections, and spring clips on the sides of said jacket adapted to engage said connecting rods whereby to hold said jacket in position upon the boiler, substantially as specified.

6. The combination with a boiler formed of a series of sections and having its front and back sections of greater outline than its intermediate sections, means for connecting said front and back sections, a jacket disposed upon said boiler intermediate its front and back sections and in spaced relation to its intermediate sections, an insulating lining

disposed between said jacket and said intermediate boiler sections, and spring clips on the sides of said jacket adapted to engage with the means for securing said boiler sections together whereby to secure said jacket 35 in position upon the boiler, substantially as specified.

7. The combination with a boiler formed of a series of sections and having its front and back sections of greater outline than 40 said intermediate sections; said intermediate sections being provided at their sides with recesses, connecting rods located in said recesses serving to secure said front, intermediate and back sections together, a jacket 45 embracing the part of the boiler intermediate said front and back sections, an insulating lining composed of a plurality of sections disposed upon the inner sides of the several parts of said jacket, and spring clips 50 on the sides of said jacket adjacent to its lower ends adapted to engage said connecting rods whereby to hold said jacket in position upon the boiler, substantially as specified.

Signed at the city of New York, in the county and State of New York, this 4th day of April, one thousand, nine hundred and twenty-one.

ANDRÉ M. MERTZANOFF.
